INVENTOR

Charles D Galloway

BY

Augustus B. Strongton
ATTORNEY.

WITNESS.

Robt. Fitchel.

UNITED STATES PATENT OFFICE.

CHARLES D. GALLOWAY, OF PHILADELPHIA, PENNSYLVANIA.

STORAGE BATTERY.

1,376,932.

Specification of Letters Patent.

Patented May 3, 1921.

Application filed December 5, 1919. Serial No. 243,602.

To all whom it may concern:

Be it known that I, CHARLES D. GALLOWAY, a citizen of the United States, residing at Philadelphia, in the county of Philadelphia and State of Pennsylvania, have invented certain new and useful Improvements in Storage Batteries, of which the following is a specification.

The principal object of the present invention is to improve, simplify and cheapen the seal connection between the jar-cover and the cell-terminal post of the plate structure.

To this and other ends hereinafter set forth, the invention comprises the improvements to be presently described and finally claimed.

The invention will be described in connection with the accompanying drawings forming part hereof and in which—

Figure 1, is a sectional view illustrative of the method of making the seal and showing features of construction.

Fig. 2, is a sectional view of so much of a battery as is necessary for an illustration of the invention, and

Figs. 3, 4, 5 and 6, are similar views showing modifications.

In the drawings 1, is a battery jar cover, 20 and 2, is a cell terminal post extending through an opening in the cover and provided with an abutment. In Figs. 1, 2, 3 and 4, the abutment takes the form of a flange 3. In Figs. 5 and 6, the abutment 35 takes the form of a tapering enlargement 3^a. In Figs. 1, 2, 3 and 5, a gasket or packing 4 or 4^a, is shown between the abutment and the cover, whereas in Figs. 4 and 6, the cover itself under pressure acts as a packing. 40 In general, this construction is not new, but the cell terminal post is shorter than usual and from this there results a saving in material. A connector shown in Figs. 1, 2, 4, 5 and 6, as an intercell connector 5, and in Fig. 3, as a terminal connector 6, is sleeved onto the cell terminal post 2, and the cover 1, and gasket or packing 4 or 4^a, when present, are gripped or 45 pressed between the connector and the flange 3, thus providing a seal connection. 50 7, is a burned or lead puddled joint provided between the connector and the terminal or end portion of the post, and this joint binds the connector to the post in

position for holding the cover and gasket, 55 when present, in pressed relation between the abutment, and the connector, thus maintaining the described seal connection.

The gasket or packing, if used, the cover 1, and the connector are strung or assembled 60 on the post 2, as shown in the drawings; then the connector and abutment are pressed toward each other, use being made of a die, as *a*, Fig. 1, and of some support as *b* for the cell terminal post 2, and while the parts 65 are pressed together, the burned or lead puddled joint 7, is made, as by introducing a flame and leaden material through the die *a*. A burned or puddled joint is well understood and it is something like a weld 70 giving rise to a practically unitary structure so that the cross-hatching in Figs. 2 and 3, is diagrammatically illustrative of puddling and lead burning, rather than of any lines of demarcation between the parts, or there 75 are really no such lines in the finished structure.

I claim:

1. In a storage battery having a jar cover and a cell terminal post extending through an opening in the cover and provided with a flange having a gasket between it and the cover, the combination with a connector sleeved onto the cell terminal post and between which and the flange the cover and gasket are gripped to form a seal, of a burned or lead-puddled joint provided between the connector and the terminal portion of the post to hold the parts in fixed sealed relation.

2. In a storage battery having a jar cover and a cell terminal post extending through an opening in the cover and provided with an abutment between it and the cover, the combination with a connector sleeved onto the cell terminal post and between which and the abutment the cover is gripped to form a seal, of a burned or lead-puddled joint provided between the connector and the terminal portion of the post to hold the parts in fixed sealed relation.

3. The method of sealing a storage battery flanged cell terminal post through a jar cover which consists in stringing a gasket and the cover and a connector on the post, 105 gripping the cover and gasket between the flange of the post and the connector by pressing the same toward each other, and

2

lead burning or puddling the connector and the terminal part of the post while the parts are pressed, substantially as described.

4. The method of sealing a storage battery cell terminal post through a jar cover which consists in stringing the cover and a connector on the post having an abutment,

gripping the cover and gasket between the abutment of the post and the connector by pressing the same toward each other, and 10 lead burning or puddling the connector and the terminal part of the post while the parts are pressed, substantially as described.

CHARLES D. GALLOWAY.
